(57) **CLAIM**

The ornamental design for an earphones and charging case set as shown and described.

DESCRIPTION

FIG. 1 is a front, top and left side perspective view of earphones of an earphones and charging case set, shown separately for ease of illustration;

FIG. 2 is a rear, bottom and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top and right side perspective view of a charging case of the earphones and charging case set, shown separately for ease of illustration and in an open configuration;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a front, top and right side perspective view of the earphones and charging case set, shown in use with the earphones received in the charging case;

FIG. 17 is a rear, bottom and left side perspective view thereof; and,

FIG. 18 is a perspective view of the charging case of the earphones and charging case set, shown separately for ease of illustration and in a closed configuration.
